UNITED STATES PATENT OFFICE

2,198,764

HAMMER

Bluford E. Edwards, Waynesboro, Tenn.

Application April 26, 1938, Serial No. 204,436

1 Claim. (Cl. 81—15)

My invention relates generally to hammers, and particularly to hammers of the type which find chief employment in sheet metal working, and an important object of my invention is to provide hammers of the character indicated which have striking surfaces which are flexibly mounted on the head of the hammer in such a way that they are self aligning with respect to the work for the purpose of preventing denting of the sheet metal when struck with the hammer head at an angle other than perpendicular to the surface being struck.

Another important object of my invention is to provide floating striking surfaces for hammers which are adapted to engage the surface to be struck in advance of the body of the head of the hammer in a manner to become aligned with the surface of the sheet metal or the like before the hammer stroke is complete.

Another important object of my invention is to provide floating striking surfaces of the character indicated which involve shock absorbing means to cushion the action of alignment of the striking surface with the surface being worked upon with relation to the body of the hammer head, whereby to prevent denting and marring of the surface struck by the hammer.

Other important objects of my invention will be apparent from a reading of the following description taken in connection with the drawings, wherein for purposes of illustration I have shown preferred embodiments of my invention.

In the drawings:

Figure 1 is a general side elevational view of a sheet metal working hammer showing floating elements mounted on the opposite ends of the head of the hammer, with one of these shown in transverse section as possessing a shock absorbing cushion.

Figure 2 is an end elevational view of one of the striking elements partly broken away.

Figure 3 is a view similar to Figure 1 but showing the shock absorbing element compressed as in the action of striking a surface with the hammer disposed at other than a perpendicular angle.

Figure 4 is a view similar to Figure 1 of another embodiment of the invention, devoid of the shock absorbing element and showing both of the floating elements in transverse section.

Figure 5 is an elevational view taken looking from left to right in Figure 4.

Figure 6 is a view similar to Figure 3 and showing the floating element assuming a compensating position.

Referring in detail to the drawings, and first

to the embodiment shown in Figure 3 thereof, the numeral 5 generally designates the shank or handle portion of the metal worker's hammer which terminates in the hammer head which is generally designated 6 which comprises the cross bar 7 with similar stationary striking elements 8 on the opposite ends thereof and each comprising a tapered portion 9 having at its outer extremity a cylindrical disk 10 which projects beyond the sides of the portion 9 and which in ordinary practice is the element which strikes the sheet metal or the like in the operation and use of the hammer. In accordance with the present invention each of the striking elements 8 is enclosed in a floating striking element 11 which comprises a cylindrical portion 12 having a closed and plain bottom 13 and having an upwardly tapered upper portion 14, the last mentioned portion 14 having inner surfaces conforming substantially in shape and outline with the contour of the tapered portion 9 when the floating striking element 11 is axially aligned with the bar 7 of the hammer head 6 as illustrated in Figure 1 of the drawings. Resting on the bottom 13 and secured thereto is a rubber or similar material shock-absorbing element 15 which has its peripheral edges circumferentially spaced from the inner wall of the cylindrical portion 12. The disk-like striking surface 10 of the hammer striking element 8 is disposed to engage this cushion 15 in the act of striking a surface to be worked upon. In the event that the hammer head in reaching contact with the work is not exactly perpendicular with the work, the bottom 13 of the element 11 will promptly assume a position flush to the surface of the work so that as the travel of the hammer head toward the work continues, the force of the hammer stroke will be communicated to the work through the agency of the element 11, the communication being cushioned and compensated as to angularity by the cushion 15 in the manner illustrated in Figure 3 of the drawings; so that the shock of the hammer blow coupled with the aligning action of the element 11 will be cushioned and absorbed, and likelihood of marring the surface struck substantially eliminated.

The elements 11 are formed of suitable steel made to shape from sheet material and may be tall and welded along one side and the bottom 50 thereof as indicated by the numerals 16 and 17 or short and crimped on the hammer to eliminate welding. While the construction of the elements 11 is not limited to this formation and arrangement or method of manufacture, I have 55

found such to be a suitable way of making the elements 11.

Referring now to the embodiment of the invention shown in Figures 4, 5 and 6, it will be found 5 that the construction and arrangement of parts is substantially similar to that described in connection with the embodiment shown in Figures 1, 2 and 3, but the absence of the shock-absorbing cushion 15 will be noted as well as a reduction 10 in the length of the tapered portion 14a of the elements 11a. In this embodiment of the invention the portion 11a of the stationary striking element 8a engages the bottom 13a of the element 11a directly and this engagement is not cushioned. 15

Although I have shown and described herein the preferred embodiments of my invention, it is to be definitely understood that I do not desire 20 to limit the application of the invention thereto,

and any change or changes may be made in the materials and in the structure and arrangement of the parts, within the spirit of the invention and the scope of the subjoined claim.

Having described the invention, what is claimed 5 as new is:

In a device of the character described, a floating striking element movably secured to a stationary striking element, said floating element comprising a cylindrical body portion having a plain 10 bottom portion and an inwardly tapered integral flange extending upwardly from the top edge portion of said cylindrical body portion, said cylindrical body portion and tapered flange portion being adapted to partially house said stationary striking element, and a cushioning element housed in said cylindrical body portion between the top surface of said plain bottom portion and said stationary element. 15
